[57] CLAIM

The ornamental design for a comet shaped scarf shaper form, as shown and described.

DESCRIPTION

FIG. 1 is a front elevational view of a comet shaped scarf shaper form showing my new design;

FIG. 2 is an end elevational view thereof;

FIG. 3 is an opposite end elevational view thereof;

FIG. 4 is a rear elevational view thereof;

FIG. 5 is a top plan view thereof, the bottom is a mirror image; and,

FIG. 6 is a front elevational view in use, the broken line showing of the human form, one comet shaped scarf shaper form, and scarf is for illustrative purposes only and forms no part of the claimed design.
